UNITED STATES PATENT OFFICE.

FAY OSCAR FARWELL, OF DUBUQUE, IOWA.

GAS-ENGINE.

No. 831,048

Specification of Letters Patent.

Patented Sept. 18, 1906.

Application filed January 21, 1901. Serial No. 44,162.

To all whom it may concern:

Be it known that I, FAY OSCAR FARWELL, a citizen of the United States, residing at Dubuque, county of Dubuque, State of Iowa, have invented certain new and useful Improvements in Gas-Engines; and I do hereby declare the following to be a full, clear, and exact description of the invention, such as will enable others skilled in the art to which it appertains to make and use the same.

My invention relates to improvements in rotary engines, and more particularly to explosive-gas engines.

The objects of my invention are to provide an engine of large power and high compression in which the cylinders revolve in a horizontal plane about a stationary axis, whereby the engine is caused to serve as its own fly-wheel, effecting a more perfect mechanical balance and eliminating the objectionable vibrations incident to the use of the ordinary type of engine when mounted on a yielding foundation—as, for example, a motor-vehicle—to provide means for keeping the engine cool without the use of a water-jacket, to secure perfect combustion of the explosive charge under all conditions, to secure a greater range of speed and to provide means for quickly changing the speed, to deaden or reduce the noise of the exhaust, and to eliminate any smoke from burning oil or imperfect mixture of the charge that may issue from the cylinders. These and other objects and advantages will appear in the following specification, particular reference being made to the accompanying drawings, illustrating my invention, and in which—

Figure 1 is a perspective view of an engine of the four-cycle type. Fig 2 is a plan view thereof. Fig. 3 is a horizontal section. Fig. 4 is a vertical section. Figs. 5 and 6 are sectional detail views of the inlet-valve on lines 5 5 and 6 6, respectively, of Fig. 2. Fig. 7 is a plan view below the line 7 7 of Fig. 4. Fig. 8 is a sectional edge view of the cam-rim for operating the exhaust mechanism. Figs. 9 and 10 are detail views of the slide device coöperating with the cam-rim. Figs. 11, 12, and 13 are detail views of the cylinder-heads and appurtenant parts. Fig. 14 is a perspective view of the wire-gauze muffler or exhaust-disintegrator.

Referring to the drawings, the main frame or casing of the engine comprises a central hollow-chamber A, from which radially project three cylinders A'. The lower open end

of the casing A is closed by a bottom plate A⁴, having a downwardly-extending column or sleeve c². Each of the cylinders A' is provided with a circumferential series of longitudinally-disposed ribs A³, and the end of said cylinders are closed by heads B, which are secured to said cylinders by any approved means.

Mounted on the top of the chamber A and 65 preferably cast integral therewith is a common inlet and mixing chamber having a central opening a, in which works an inwardly-opening valve a³, which is connected to a bell-crank lever a¹⁴, pivotally mounted upon a 70 connection a⁶. The other end of said lever a¹⁴ receives a rod a¹³, which carries a spring a⁴ to adjust the tension of said lever, and thereby determine the throttling action of the valve a³. Said spring is adjusted by 75 means of a serrated wedge a²⁴, which slides between the spring and a securing-nut upon the end of the rod. The coupling a⁶, which is mounted upon a stationary ring a², bearing upon the upper side of the mixing-chamber 80 and retained in position by an upwardly-turned flange surrounding the opening a, is connected with a suitable supply-pipe a⁵ for the explosive fluid, and said coupling constitutes a valve-casing for a needle-valve a⁷, 85 which regulates the supply of such explosive fluid. The ring a² is held in proper position on the upper side of the mixing-chamber by the supply-pipe a⁵ and the coupling a⁶. Said supply-pipe may be rigidly attached to the 90 fluid-tank exterior to the engine. Of course, if it is desired, the ring a² may be held in position by a separate rod or bracket secured thereto and to a stationary support adjacent to the engine. An angle-pipe a²⁵, connected 95 with said coupling, delivers the charge of explosive fluid at a point above the valve a³ and said pipe a²⁵ is closed by a valve a⁸ in the end thereof which is connected with the lever a¹⁴ and is adapted to be operated 100 simultaneously with the operation of the valve a³.

Opening into the common inlet and mixing chamber are three passages a', which communicate with tubular passages a²¹, 105 which in turn open into passages b', terminating in inlet-ports for the respective cylinders. Each of the inlet-ports is closed by an inwardly-opening valve b², which finds a seat on the inner side of the cylinder-head.

Formed on the cylinder-head B in juxtaposition to the passage b' is an exhaust-port

closed by an inwardly-opening valve b^3 , which is normally held to its seat by a spring b^8 . Positioned in said exhaust-port is a binding-post b^4 , which carries the sparking terminal of the igniting mechanism. Said igniting mechanism comprises an annular commutator-ring of three conducting-sections n , mounted in an insulating-ring secured to the top of the casing. A stationary insulated brush is connected with the source of current and comprises a bearing-block a^{12} in contact with the commutator-ring, an insulating-bushing a^{18} , secured in a fixed support a^9 , a housing a^{10} , carrying a spiral spring a^{17} to supply the necessary tension to said bearing-block, and a binding-post a^{16} , whose inner end bears upon the spiral spring a^{17} . The respective sections n of the commutator-ring are connected to the individual sparking plugs b^4 by conducting-wires x , and the return-lead to the source of current is connected to the engine-casing, as illustrated in Fig. 1.

A base plate or support C is provided with an upwardly-extending flanged bearing c^{10} , which supports the sleeve c^2 of the main casing. Rigidly fixed in the bearing-plate C is a hollow crank-shaft c , which fits snugly within the sleeve c^2 . Said crank-shaft terminates in a disk c^9 , bearing upon the bottom plate a^4 , from which disk projects the crank or wrist pin c^3 . Secured to the crank or wrist pin c^3 by means of suitable pitmen c^4 are three hollow pistons P, which engage the respective cylinders A'. The respective pitmen are connected to the wrist-pin by segmental foot-pieces c^{11} , each of which has a bearing upon the surface of the wrist-pin somewhat less than one-third of the total surface of said pin; and the parts are secured in position by tapered rings c^5 , which engage with like tapers on the foot-pieces of the pitmen and hold the parts in a secure and adjustable relation. The central orifice c^6 of the crank-shaft opens into the casing A and affords an intake for a current of air which is exhausted through lateral pipes A², connected to the casing between the respective cylinders. The crank-shaft c is also pierced with a longitudinal duct c^7 , which is in communication with a supply of cooling-water and lubricating-oil by means of the pipe c^8 .

Fixed to the base C by means of suitable standards d'' is an exhaust-operating cam D, which has in its upper face two generally parallel grooves d' , which intersect at d^2 . The outer groove has a raised surface for one-half of its circumference, (indicated at d^3 in Fig. 4.) The inner groove and the remaining one-half of the outer groove, including the intersection at d^2 , are in a common plane.

d^4 is a rocker-shaft, to the outer end of which is secured the exhaust-valve-operating lever b^5 . To the inner end of the rocker-shaft is pivoted a link d^6 , secured by a suit-

able ball-and-socket joint to a shoe d^8 , which operates in the grooves d' of the cam-ring D.

Surrounding the sleeve c^2 and mounted in the bearing c^{10} of the base-plate C is the speed-regulating sleeve E. The lower end of this sleeve is notched to provide three cams c^{13} , which co-operate with similarly-disposed cams e on the bearing c^{10} . On the top of this sleeve rests a loose washer e^2 , and in the upper face of this washer e^2 is provided a recess e^3 , as shown in Fig. 7.

Secured to the sleeve c^2 are three bell-crank levers F, which are connected at their upper ends to the governing-springs b^7 and rest with their opposite ends bearing upon the washer e^2 . The outer end of each governing-spring b^7 is secured to a pivoted lever b^6 , mounted in ears on the cylinder-heads B, and said levers b^6 are adapted to lie adjacent to the downwardly-projecting stems of the exhaust-valves b^3 , which stems are provided with the depressions b^{13} , which under certain conditions are engaged by the lever b^6 to hold the valve b^3 open. A suitable handle e' , connected with the sleeve E, is provided for rotating the sleeve bodily, causing the same to rise as the cams c^{13} and e engage. When this sleeve is moved in the direction indicated by the arrow in Fig. 1, the cams on the bottom of the sleeve will ride upon the cam-lugs e and the sleeve will be raised, causing the bell-cranks to be rocked and the governing-springs b^7 to be tightened.

Through each of the cylinders A' are drilled a series of auxiliary exhaust-ports G, which are uncovered by the piston at the inner end of its stroke. These ports are located between contiguous ribs A³, preferably on the rear side of the cylinder—that is to say, on the side opposite the direction of motion of said cylinder—but, as shown, the ports are located on both the front and rear sides of the cylinders. Covering each of these auxiliary exhaust-ports is a roll of gauze g' , all of which are held in position by means of a perforated plate g^2 , secured to the ribs. The gauze rolls and the perforated plates are omitted from the rear ports G in the various views to avoid unnecessary complication in the drawings; but it is to be understood that I may employ the said exhaust-ports and coverings on either or both sides of the cylinders.

The operation of the engine described above is as follows: It will be understood that the casing, the cylinders, and the pistons rotate about the fixed crank-shaft c and that the moving parts constitute a fly-wheel. This engine operates on what is known as the "four-cycle" principle, and its complete operation may be best followed by taking a single cylinder, as X in Figs. 1 and 3, and tracing its action throughout a complete cycle. In the position indicated the piston is at its extreme inward stroke. For the purpose of

illustration we will consider this to be the end of the explosive or power stroke. Now with the cylinders revolving in the direction indicated by the arrow the piston will approach the cylinder-head and the contents of the cylinder will be blown out of the exhaust-valve b^3 , which is open for the purpose. When the cylinder has reached a position diametrically opposite to that indicated at X, the piston will have reached the end of its outer stroke. As it continues to revolve the piston again recedes and creates a vacuum in the cylinder, and the spring b^8 , which holds the exhaust-valve closed, being quite stiff, the inlet-valve b^2 is forced open by the mixed charge of the explosive gases and air which enters through the opening a , passages a' , a^{12} , and b' filling or partly filling the cylinder, according to the amount of resistance or throttling which occurs at the valve a^3 . When the cylinder has again reached the position X and the piston is at the end of its inner stroke, should there be any vacuum or rarefaction of the gases in the cylinder caused by the resistance or throttling at the explosive mixture, pure air would be drawn in through the auxiliary ports G to supply this vacuum or compensate for the rarefaction. As the cylinders continue to revolve the piston again approaches the cylinder-head and compresses the explosive mixture until it reaches the position nearly opposite to that indicated at X, when the block a^{12} comes in contact with the proper commutator-section n , completing the circuit to the sparking plug b^4 of the cylinder, and the explosive mixture is fired. The remaining one-half revolution is a power-stroke. When the cylinder again reaches the position marked X, the piston uncovers the auxiliary exhaust-ports G and the terminal pressure of the explosive charge is allowed to escape through the gauze mufflers g' . This brings the cylinder under consideration to the initial position X, where it is ready to begin another cycle. In the above-described operation the explosive fluid, which may be oil, gasoline, gas, or any other suitable fluid, is admitted through the pipe a^3 , and as the valve a^3 is drawn inward by the suction-stroke of a piston it carries with it the valve a^8 in the end of the supply-pipe, thereby admitting a charge of explosive fluid and air through the valve a^3 into the common mixing-chamber. The amount of the explosive fluid admitted through pipe a^{25} is regulated by the needle-valve a^7 , and the operation of valve a^3 in admitting the mixed charge is determined by the spring a^4 , whose tension is adjusted to regulate the amount of throttling desired by the wedge a^{24} . The combined charge is drawn into the mixing-chamber and the connecting passages at each suction-stroke of a piston and passes through the port, closed by the inwardly-opening valve b^2 , into the cylinder. The ac-

tion of the exhaust mechanism is as follows: In the original position (indicated at X) the shoe d^6 of the exhaust-valve-operating mechanism is in the outer groove of the ring D, and as the cylinder continues to revolve the shoe ascends the incline d^3 and by means of the rocker-shaft d^4 and its connecting parts opens the exhaust-valve b^3 and holds it open for one-half revolution, or until the piston has reached the outer limit of its stroke near the piston-head. As the engine continues to revolve the shoe, which is still in the outer groove, crosses to the inner groove, and during the next one and one-half revolutions the exhaust-valve is closed, during which time the explosive charge is compressed, exploded, and expanded. Should the speed of the engine be too great, so that the centrifugal force acting upon the long end of the lever b^6 would overcome the strength of b^7 , said lever would be thrown out against the stem of the exhaust-valve, and when said valve has been raised to its highest point this lever will drop into the notch b^{13} in the stem of the exhaust-valve and prevent the valve closing. As the cylinders revolve and the piston again commences its suction-stroke air will be drawn in through the exhaust-valve instead of an explosive charge being drawn through the inlet-valve b^2 . There will therefore be no power-stroke for this cycle, and the exhaust-valve will be held open by the lever b^6 until the speed of the engine has been so far reduced that the strength of the spring b^7 is greater than the centrifugal force on the long end of the lever b^6 , when the spring will draw said lever out of engagement with the stem and the valve will close and an explosive charge will be admitted at the next suction-stroke. It will be seen that the levers b^6 act as an automatic governor for the speed of the engine, as when the speed becomes excessive they are effective in throwing one or more of the cylinders out of action until the speed decreases. Should it be desired to drive the engine at a higher rate of speed than the normal, it will be necessary to regulate the action of the levers b^6 , which is accomplished by moving the sleeve E in the direction indicated by the arrow in Fig. 1, when the sleeve is raised by the coöperation of the cams c^{13} and e , as before described, thereby rocking the bell-cranks to increase the tension of the springs b^7 , which therefore require a greater centrifugal force and a corresponding increase in the speed of the engine to overcome their tension. In operating gas-engines of this kind it is frequently found that the normal power required will be furnished by two of the cylinders alone, while the third remains idle. I have found it very desirable under such conditions to cool the idle cylinder, and this I accomplish by the coöperation of the bell-cranks F and the depression e^3 in the washer e^2 . The lower end of one of the bell-

crank levers will drop into this depression, and thereby release the tension on the spring b^7 , which is connected with said lever, and permit the exhaust-valve governed by said 5 spring to be held open by the lever b^6 , so that the corresponding cylinder will be thrown out of action, and as the piston reciprocates therein it will draw in and blow out air, which will quickly cool the cylinder and appurtenant parts. By adjusting the sleeve E so that the several bell-cranks will occupy the depression e^3 successively each of the cylinders in turn may be thrown out of operation and cooled off by drawing in and exhausting 10 air through the exhaust-valve. It will be apparent that the ring E is moved through a small angular distance by handle e' to raise and lower the said sleeve to increase or diminish the speed of the engine. The ring e^2 15 lies loosely on top of the sleeve E, and when the sleeve is in its lowest position the ends of the bell-cranks F do not engage the ring e^2 . Hence said ring does not rotate. When the sleeve E is raised, by means of the cams e and 20 levers e' , the ring e^2 will come in contact with the ends of the bell-cranks F, and one of said ends will drop into the depression e^3 , thereby causing the ring e^2 to rotate with the bell-crank, with the result that the spring b' 25 attached to that particular bell-crank will be weakened, thereby permitting the exhaust-valve controlled by said spring to be opened, thus throwing the cylinder controlled by said valve out of operation and 30 causing it to pump air. I also provide a second means for governing the engine by means of the valve a^3 and the inlet-valves b^2 . If the spring a^4 , which holds the valve a^3 in closed position, is weak, very little resistance 35 is offered to the entrance of the explosive charge through the opening a , connecting-passages, and valve b^2 ; but if this spring is strengthened and the resistance to the opening of the valve is sufficient to cause a considerable vacuum in the cylinder at the end 40 of the suction-stroke the cylinder will only be partly filled with the explosive mixture. This vacuum would be supplied by pure air entering through the auxiliary exhaust-ports G. 45 This entering supply of air is prevented from mixing with and diluting the explosive charge by the centrifugal force of the rotating parts, which forces the heavier explosive gas outward against the cylinder-head, where it surrounds the sparking terminal, while the air forms a cushion between the piston and the charge. The explosive charge would, therefore, be weak and the resultant power-stroke 50 correspondingly diminished. The valve b^2 is 55 provided with a vertical seat and is normally held to its seat by the centrifugal force of the revolving cylinders. Hence in starting the engine when it is turned slowly by hand and a small charge of explosive mixture is admitted into the mixing-chamber this valve is

drawn open and the centrifugal force is not sufficient to close it. The charge would, therefore, be drawn into the cylinder and on the return of the piston would be blown back past valve b^2 and drawn into the other cylinders successively as long as the engine turns slowly. The particular advantage of this operation is manifest especially in using gasoline as an explosive fluid. In cold weather this does not evaporate readily, and it is difficult to get it thoroughly mixed with air to make the charge ignite easily; but if the engine is turned slowly for a few turns the air circulates from one cylinder to another over this liquid gasoline until it is thoroughly mixed. Then if the speed of the engine is increased slightly centrifugal force will close one or more of the valves b^2 when the charge has been drawn in. This charge will be compressed by the fly-wheel effect of the revolving engine and exploded, and the engine will thus be started. By utilizing centrifugal force only for closing the inlet-valve b^2 I am enabled to procure a thoroughly-mixed explosive charge and at the same time relieve the compression of the engine until sufficient momentum or speed is obtained to close the valve b^2 . By utilizing centrifugal force to close the valve b^2 the force required to open the same is directly in proportion to the speed of the engine, being greater when the engine runs fastest, and this in itself constitutes a governor, which would prevent the engine from racing. In starting the engine the amount of the charge of the explosive gases 100 may be small and the vacuum produced in the cylinder would be supplied through the auxiliary ports G, thereby establishing a cushion of light air behind the explosive charge, which charge would be compressed 105 by the centrifugal action between the air-cushion and the head of the cylinder. Hence the gases in the head of the cylinder surrounding the igniter would be sufficiently rich to readily ignite.

The spring a^4 is made stronger when it is desired to reduce the power of the engine, and, conversely, it is weakened when the engine is to run at a higher rate. The tapering block shown which slides between the spring 110 and the nut for adjusting the tension of said spring may be connected by any suitable operating-lever.

I have found with an engine constructed as described above that water-jackets for cooling the cylinders and the other engine parts are wholly unnecessary. With my device the cylinders revolve through the air at a rapid rate. The air in contact with the cylinders and radiating ribs is constantly and rapidly 115 changed. The centrifugal action of the rotating parts serves to draw in air through the opening c^6 of the shaft c, which is immediately exhausted through the tubes A^2 , thereby 120 constantly supplying the interior of the cas- 130

ing with fresh air. I have found that under normal conditions the air-cooling means is entirely sufficient. However, when the maximum power is required for a considerable period it is desirable to cool the pistons, and a supply of cooling-water is drawn in through the duct *c* and to the interior of the pistons and kept in contact with the piston-head by the centrifugal action.

10 As before mentioned, another object of my invention is to deaden or reduce the noise of the exhaust and eliminate the discharge of smoke from burning oil or unconsumed gases. This I accomplish by the particular arrangement 15 of the auxiliary exhaust-ports *G* and the gauze covers therefor. As will be seen by reference to Fig. 1, the ports *G* are drilled into the cylinder between the radiating ribs on the side of the cylinder opposite the direction of rotation. The exhaust therefore shoots against receding air in the series of small jets, which is effective in breaking up the exhaust-gases and rendering the noise of the escape thereof almost inaudible and 20 wholly without the sharp explosion or crackling noise incident to gas-engines of the ordinary type. I further reduce this noise and eliminate the escape of smoke by covering the exhaust-opening *G* with rolls of wire- 25 gauze *g'*, placed between contiguous ribs. This serves to effectively break up and distribute the exhaust-gases and the smoke which is thrown out into the air that is in rapid motion in the same direction as very small particles or sprays, which renders the smoke entirely invisible and the noise almost inaudible. 30

By the arrangement of the cylinders, which open into the central casing *A* a slight distance above the bottom plate *A*⁴, I obviate 35 the objectionable flooding of any of the cylinders with lubricating-oil, as the oil will drain from the cylinders into the center of the casing as soon as the engine comes to rest.

A practically perfect balance of the engine 40 is obtained by the construction shown in that the three cylinders revolving in a horizontal plane rotate about the shaft *c* while the pistons and connecting parts center about the crank-pin. The respective cylinders with 45 their appurtenant parts are made of exactly the same weight, and therefore will produce no uneven strain or torque. This feature is particularly desirable when the engine is used in connection with a motor-vehicle 50 where the engine is suspended upon springs. As the engine revolves in a horizontal plane, the springs upon which it is supported would neither be compressed nor expanded and the very disagreeable rocking or vibration which 55 is noticeable in vehicles using vertically-reciprocating engines would be eliminated.

It will be seen, therefore, that I have produced an engine that acts as its own fly-wheel, that is self-regulating for a given 60 speed or power, that may be immediately ad-

justed through a wide range of speeds by regulating the throttling action of the supply-valve or adjusting the regulator-springs of the exhaust-valves, that is cooled by a continuously-renewed supply of air, that is self-lubricating, that emits no smoke and produces very little noise at the exhaust, and that rotates in a substantially perfect mechanical balance without objectionable vibration. These qualities render my engine 70 particularly well adapted for use in connection with motor-vehicles.

Having thus described my invention, what I claim is—

1. A gas-engine comprising a stationary 80 crank-shaft, a series of coöperating cylinders and pistons rotating about said crank-shaft, means for supplying an explosive charge to the cylinders, means for supplying air between the piston and said charge, and means 85 for igniting and exhausting said charge.

2. A gas-engine comprising a stationary crank-shaft, a series of coöperating cylinders and pistons rotating about said shaft, means for supplying an explosive charge to said cylinders, an air-inlet in each cylinder adjacent the inner limit of the piston travel whereby a cushion of air is admitted between the piston and said charge, and means for igniting and exhausting said charge. 95

3. A gas-engine comprising a stationary crank-shaft, a series of coöperating cylinders and pistons rotating about said shaft, means for supplying an explosive charge to said cylinders, a combined air inlet and exhaust adjacent the inner limit of the piston travel comprising a series of orifices whereby the air is admitted next to the piston at the end of the suction-stroke and the exploded gases are partially exhausted at the end of the 100 power-stroke, and means for igniting and finally exhausting said charge. 105

4. An explosive-gas engine provided with means for muffling the exhaust, comprising a series of orifices in the cylinder near the limit 110 of the power-stroke, and means near said orifices to dissipate the exhaust-gases.

5. An explosive-gas engine comprising a stationary crank-shaft, a series of coöperating cylinders and pistons rotating about said 115 shaft, and a series of longitudinal ribs on said cylinders, each cylinder being provided with a series of exhaust-openings between the ribs on the cylinder on the side opposite the direction of motion of said cylinder, whereby the 120 noise of the exhaust is reduced.

6. An explosive-gas engine comprising a cylinder, piston and coöperating parts, a series of longitudinal ribs on said cylinder, a series of exhaust-orifices between said ribs, and 125 means carried between contiguous ribs and adjacent to said orifices to dissipate the exhaust-gases.

7. An explosive-gas engine comprising a cylinder, piston and coöperating parts, a se- 130

- ries of longitudinal ribs on said cylinder, a series of exhaust-orifices between said ribs, and rolls of wire-gauze between contiguous ribs and adjacent to each orifice to dissipate the 5 exhaust-gases.
8. An explosive-gas engine comprising a cylinder and piston, a hollow stationary crank-shaft, and a hollow casing communicating with and rotating about said shaft, 10 said casing having peripheral openings, whereby air is drawn in through said shaft and expelled through said openings to cool the engine parts.
9. An explosive-engine comprising a stationary crank-shaft having a longitudinal duct, a hollow casing revolving in a horizontal plane about said crank-shaft, radially-disposed cylinders opening into said casing, hollow pistons working in said cylinders and operatively connected to said crank-shaft, and a source of cooling-water connected to said crank-shaft duct, whereby water will be forced into said casing and cylinders to cool the same.
- 15 10. An explosive-gas engine comprising a cylinder and piston, a vertical hollow stationary shaft, a hollow engine-casing communicating with and rotating about said shaft, and a series of radial tubes opening into said 20 casing, whereby air is drawn in through said shaft and expelled through said tubes to cool the engine parts.
11. An explosive-gas engine comprising a stationary crank-shaft, a hollow casing carrying coöperating cylinders and pistons rotating about said shaft, a common adjustable supply-valve for admitting predetermined amounts of explosive fluid and air, an 25 exhaust-valve for each cylinder, means for operating the same, and means controlled by centrifugal force to hold the exhaust-valve open when the speed of the engine becomes excessive.
12. An explosive-gas engine, comprising a stationary crank-shaft, coöperating cylinders and pistons rotating about said shaft, an inlet-valve for each cylinder opened under the 30 suction action of the piston during the inlet- stroke, an exhaust-valve for each cylinder, means for operating the same, an adjustable spring-actuated means coöperating with said exhaust-valve to hold the same open when the speed of the engine becomes excessive, and means for regulating the tension of the adjustable spring, thereby controlling the 35 action of the exhaust-valve.
13. An explosive-gas engine, comprising a stationary crank-shaft, coöperating cylinders and pistons rotating about said shaft, an inlet-valve for each cylinder held to its seat by centrifugal force and opened under the suction action of the piston during the inlet- stroke, an exhaust-valve for each cylinder, means for operating the same, and adjustable means for holding an exhaust-valve 40 open, whereby the corresponding cylinder is thrown out of operation.
14. An explosive-gas engine comprising a stationary crank-shaft, a hollow casing carrying coöperating cylinders and pistons rotating about said shaft, an inlet-valve for each cylinder, an exhaust-valve for each cylinder, means for operating the same, and means coöperating with said exhaust-valves whereby said valves are held open successively and the respective cylinders are cooled by drawing in and discharging air.
15. An explosive-gas engine, comprising a stationary crank-shaft, coöperating cylinders and pistons rotating about said shaft, an inlet-valve for each cylinder held to its seat by centrifugal force and opened by an explosive charge, an exhaust-valve for each cylinder, means for operating the same, a spring-pressed lever coöperating with said exhaust- 50 valve to hold the same open when the pressure of said spring is relieved, and means to adjust the tension of said spring, whereby the action of the exhaust-valve is controlled and the speed of said engine may be regulated.
- In testimony whereof I affix my signature in presence of two witnesses.
